UNITED STATES PATENT OFFICE.

ALFRED P. BABCOCK, OF BROOKLYN, NEW YORK.

DESIGN FOR A PERFUMERY-BOTTLE.

SPECIFICATION forming part of Design No. 20,993, dated August 18, 1891.

Application filed March 23, 1891. Serial No. 386,177. Term of patent 14 years.

To all whom it may concern:

- Be it known that I, ALFRED P. BABCOCK, a citizen of the United States, residing at Brooklyn, in the county of Kings and State of New York, have invented and produced a new and original Design for a Perfumery-Bottle, of which the following is a specification, reference being had to the illustration forming a part hereof, in which the design is shown.
- 5 The leading characteristic or feature of my design consists in a bottle having the shape or configuration of a conventionalized lantern provided with the surface ornamentation herein shown.
- 10 A is the upper part of the design of the configuration shown, above which is the neck B of the bottle, having a spiral groove b.
- 15 C is the body or central portion of the de-

sign, which is globular in form, and upon which are ribs c, dividing the surface of the central portion vertically and horizontally in more or less rectangular panels. Below the globular section C is a base or pedestal D, which is of the configuration indicated and of a diameter which corresponds substantially with the diameter of the upper portion A.

What I claim is—

The design for a bottle herein shown and described.

Signed at New York, in the county of New York and State of New York, this 18th day of March, A. D. 1891.

ALFRED P. BABCOCK.
